CLAIM

The ornamental design for a sign, as shown and described.

DESCRIPTION

FIG. 1 is a perspective view of a first embodiment of a sign showing our new design;

FIG. 2 is a front elevational view thereof;

FIG. 3 is a back elevational view thereof;

FIG. 4 is a right-side elevational view thereof;

FIG. 5 is a left-side elevational view thereof;

FIG. 6 is a top plan view thereof;

FIG. 7 is a bottom plan view thereof;

FIG. 8 is a front elevational view of a second embodiment, a back elevational view being a mirror image thereof;

FIG. 9 is a front elevational view of a third embodiment; and,

FIG. 10 is a back elevational view thereof.

The the right-side elevational view, left-side elevational view, the top plan view, and the bottom plan view of the second and third embodiments are the same as the first embodiment's views shown in FIGS. 4-7, respectively.

Broken lines in the figures show portions of the sign that form no part of the claimed design. Dash-dot broken lines in FIGS. 9-10 define the bounds of the claimed design and form no part thereof.
